WINDOW CONSTRUCTION

August C. Fast, Detroit, Mich., assignor to
 Car-Kra Corporation, Detroit, Mich., a Corporation of Michigan

Application September 9, 1932. Serial No. 632,405

8 Claims. (Cl. 20—49)

The present invention pertains to a novel window construction of the sliding sash type, and the principal object is to provide such a construction wherein the sliding sash may be swung on a horizontal axis either to a partially open, ventilating position or to a fully open position enabling access to the outer surface of the window pane from the interior of the building for cleaning.

10 Another object is to provide means whereby the tilting action of the sash becomes possible only in certain vertical positions of the sash. Accordingly, there is provided in the window construction a latch which holds the sash against tilting, and this latch is disengaged only by contact with selectively located abutments in the window frame.

20 The invention further provides means for limiting the sliding movement of the sash while in open position. An automatic stop for this purpose becomes operative and enters a slot in the fixed structure when the sash is tilted. Other and incidental objects of the invention will appear as the description proceeds.

25 The invention is fully disclosed by way of example in the following description and in the accompanying drawing, in which—

Figure 1 is a vertical section of a window equipped according to the invention;

30 Fig. 2 is a side elevation of the window slide and parts associated therewith;

Figs. 3, 4, 5, and 6 are sections on the lines 3—3, 4—4, 5—5 and 6—6 respectively of Figure 2, and

35 Fig. 7 is a sectional view corresponding to Figure 6 and showing the slide detent in holding position on pivotal displacement of the sash.

Reference to these views will now be made by use of like characters which are employed to designate corresponding parts throughout.

40 In several of the views is illustrated a conventional window frame 1 having the usual strips or moldings 2 forming grooves or channels 3 for slidably supporting the window sashes. According to the invention, however, a channel slide 4 rather than the wooden sash frame is slidably mounted in the groove 3. The solid back 5 of the slide is disposed within the window opening, as shown in Figure 5, and is formed at one edge with a retaining and stop flange 6 for a purpose which will presently appear. To the lower end of the slide 4 is pivotally attached a sash plate 7 by means of a pivotal construction indicated generally by the numeral 8 in Figure 5. The pivot may be of any construction suit-

able for affording two different adjustments of the member 7 relatively to the slide 4 and may for example be made as shown in my United States Patent No. 1,774,088 of August 26, 1930. The conventional wood sash frame 9 is secured to the sash plate 7 by a suitable number of screws 10 as clearly shown in Figures 3, 4 and 5. The parts 4 and 7 are preferably of metal, and it is also preferred that a unit of the type described herein be provided in each side of the window frame. 60

The backing 5 of the channel 4 carries an assembly plate 11 on the side facing the wood frame 1. Various parts of the mechanism are mounted on this plate before the latter is secured to the channel slide 4. The plate 11 is 70 formed with an ear 12 on which is pivotally mounted a latch 13. The plates 11, 5 and 7 are formed with registering slots 14, 15 and 16 respectively adapted to receive the lower end 17 of the latch 13 to lock the sash plate to the slide. 75 The upper end of the latch is formed as a cam 18 engaged by a flat spring 19 secured to the plate 11, whereby the lower end 17 is normally urged to locking position.

The bottom of the window frame groove 3 has a control plate 20 secured thereto by screws 21 as clearly shown in Figures 3, 4 and 5. This plate has one or more abutments 22 extending toward the slide 4 and in the vertical path of the cam end 18. When one of these abutments is engaged by the cam 18 in the vertical sliding movement of the sash and slide 4, the locking end 17 of the latch is retracted to the released position shown in Figure 3, whereupon the sash with its sash plate 7 is free to swing as shown in Figure 1. The nature of the pivotal attachment 8 is such as to permit the partially open or ventilating position shown in Figure 1 and also a more fully opened position permitting access to the outer surface of the glass 23 for cleaning as 90 the sash is swung into the room. When the sash is in closed position, an edge of the plate 7 is received behind the retaining flange 6 which thus serves as a stop for the closing movement of the sash and also prevents tilting the sash in the 95 wrong direction.

In order to avoid raising the sash while in tilted position, there is provided a stop between the slide and the window frame, operable on tilting of the sash. The control plate 20 has vertical slots 24 corresponding to the abutments 22, and the metal at the ends of these slots is bent inwardly of the groove 3 as indicated by the numeral 25. To the assembly plate 11 is secured a flat spring 26 carrying at its free end a stop 105 110 115

adapted to enter one of the slots 24 when the cam end 18 is engaged by the corresponding abutment 22.

Over the spring 26, a horizontal ear 28 is struck out of the plate 11 and has a bell crank lever 29 pivoted thereto, one end of the lever engaging the upper extremity 30 of the spring 26 in a manner to push it toward the back 5 of the slide 4 when the other end of the lever is pushed into the slide, as illustrated in Figure 6. The last named end of the bell crank lever registers with a slot 31 in the back 5 of the slide 4 and is engaged by the sash plate 7 in the closed position of the sash. In this position, the bell crank lever compresses the spring 26 toward the plate 11 and holds the stop 27 out of the slot 24. When, however, the sash is swung on release of the latch 13, the sash plate 7 clears the free end of the bell crank lever 29, permitting this end to project through the slot 31 as shown in Figure 7, whereupon the spring 26 throws the stop 27 into one of the slots 24 of the fixed control plate 20, so that the slide 4 cannot be moved farther than the length of a slot 24.

When the sash is tilted out of contact with the upper ends of the opposed slides 4, the latter are likely to lean away from the grooves 3 and towards the interior of the window opening. In order to overcome this tendency, the control plate 20 is formed at one of its vertical edges with a shoe or indent flange 32. The assembly plate 11 carries a hooked lug 33 adapted to engage behind this flange when the latch 13 is released by contact with one of the abutments 22, as illustrated more clearly in Figure 3. The interengagement of parts 32, 33 obviously holds the slide from tilting into the window opening.

It is desirable to maintain the channel member 4 as shallow as possible in order not to reduce the width of the window opening any more than absolutely necessary. The usual sash cord must obviously be secured within the member 4, and the usual knot at the attached end of the cord would require corresponding depth in the channel 4 or would interfere with parts of the plate 20. Accordingly, the invention provides means for securing the cord in a flat condition or without the usual knot.

At the upper end of the assembly plate 11 is formed a loop 34 through which the sash cord 35 is threaded. Below the loop, a downwardly extending hook 36 is struck out of the plate 11, and the cord 35 is carried beneath this hook. Between the loop 34 and hook 36, a laterally extending hook 37 is struck out of the plate 11, and the cord 35 is then carried over this hook. Both hooks are hammered or otherwise pressed against the cord, whereby the latter is anchored in a flat or thin condition and without the usual knot.

It will now be seen that the sash is in condition for tilting only when in certain vertical positions determined by the abutments 22. Moreover, on tilting of the sash, a stop device for limiting the sliding of the sash comes into action. Also, in these positions, inward tilting of the slides disengaged by the sash is prevented. The special anchorage of the sash cord makes possible a comparatively shallow channel slide 4 which takes up very little of the width of the window opening.

Although a specific embodiment of the invention has been illustrated and described, it will be understood that various alterations in the details of construction may be made without de-

parting from the scope of the invention, as indicated by the appended claims.

What I claim is:

1. In a window, a frame, a slide movable in said frame, a sash plate pivoted to said slide, a sash secured to said plate, a latch normally locking said plate to said slide to hold said sash against tilting, means in said frame engageable by said latch for releasing the latter from said plate, a stop carried by said slide and tending to engage with said frame, said plate normally holding said stop out of engagement with said frame, whereby said stop is released for engagement with said frame on removal of said plate from said slide.

2. In a window, a frame, a slide movable in said frame, a sash plate pivoted to said slide, a sash secured to said plate, a latch normally locking said plate to said slide to hold said sash against tilting, means in said frame engageable by said latch for releasing the latter from said plate, a retaining member carried by said frame, and means carried by said slide and adapted to lock with said retaining member on engagement of said latch with the first named means.

3. In a window, a frame, a slide movable in said frame, a sash plate pivoted to said slide, a sash secured to said plate, a latch normally locking said plate to said slide to hold said sash against tilting, means in said frame engageable by said latch for releasing the latter from said plate, a retaining member carried by said frame, means carried by said slide and adapted to lock with said retaining member on engagement of said latch with the first named means, a stop carried by said slide and tending to engage with said frame, said plate normally holding said stop out of engagement with said frame, whereby said stop is released for engagement with said frame on removal of said plate from said slide.

4. In a window, a frame, a slide movable in said frame, a sash plate pivoted to said slide, a sash secured to said plate, a latch normally locking said plate to said slide to hold said sash against tilting, a control plate secured to said frame, means in said control plate engageable by said latch for releasing the latter from said sash plate, said control plate having a slot, a stop carried by said slide and tending to enter said slot, said sash plate normally holding said stop out of engagement with said slot, whereby said stop is released for engagement in said slot on removal of said sash plate from said slide.

5. In a window, a frame, a slide movable in said frame, a sash plate pivoted to said slide, a sash secured to said plate, a latch normally locking said plate to said slide to hold said sash against tilting, a control plate secured to said frame, means in said control plate engageable by said latch for releasing the latter from said sash plate, a retaining member carried by said control plate, and means carried by said slide and adapted to lock with said retaining member on engagement of said latch with the first named means.

6. In a window, a frame, a slide movable in said frame, a sash plate pivoted to said slide, a sash secured to said plate, a latch normally locking said plate to said slide to hold said sash against tilting, a control plate secured to said frame, means in said control plate engageable by said latch for releasing the latter from said sash plate, said control plate having a slot, a stop carried by said slide and tending to enter said slot, said sash plate normally holding said stop out of engagement with said slot, whereby said stop

is released for engagement in said stop on removal of said sash plate from said slide, a retaining member carried by said control plate, and means carried by said slide and adapted to lock 5 with said retaining member on engagement of said latch with the first named means.

7. In a window, a frame, a slide movable in said frame, a sash plate pivoted to said slide, a control plate in said frame, said control plate having 10 an abutment and a slot, a latch normally locking said sash plate to said slide to hold said sash against tilting, a movable stop in said slide adapted to enter said slot, means connected to said stop and engaged by said sash plate for normally retracting said stop from said slot, and means carried by said latch for engaging said abutment when said stop is in line with said slot to release said sash plate for pivotal movement whereupon said stop enters said slot.

20

8. In a window, a frame, a slide movable in said frame, a sash plate pivoted to said slide, a control plate in said frame, said control plate having an abutment and a slot, a latch normally locking said sash plate to said slide to hold said sash against tilting, a movable stop in said slide adapted to enter said slot, means connected to said stop and engaged by said sash plate for normally retracting said stop from said slot, means carried by said latch for engaging said abutment when said stop is in line with said slot to release said sash plate for pivotal movement whereupon said stop enters said slot, a retainer member on said control plate, and means carried by said slide 80 for engaging said retainer member when said means on said latch registers with said abutment to prevent movement of said slide out of said frame.
